UNITED STATES PATENT OFFICE.

JOHN WILLISON, OF DERBY, ENGLAND, ASSIGNOR TO THE NATIONAL MALLEABLE CASTINGS COMPANY, OF CLEVELAND, OHIO.

CAR-COUPING.

1,201,666.

Specification of Letters Patent. Patented Oct. 17, 1916.

Application filed December 31, 1913, Serial No. 809,601. Renewed August 10, 1916. Serial No. 114,293.

To all whom it may concern:

Be it known that I, JOHN WILLISON, a subject of the King of Great Britain, and a resident of Derby, county of Derby, England, have invented new and useful Improvements in Car-Couplings, of which the following is a specification, reference being had to the accompanying drawings, in which—

10 Figure 1 is a plan of a pair of interlocked couplers embodying my improvements; Fig. 2 is a section on lines II—II of Fig. 1; Fig. 3 is a plan of a coupler with the parts in lowermost position; Fig. 4 is an 15 elevation with the parts in lowermost position; Fig. 5 is a front elevation with the parts in lock-set position; Fig. 6 is a section on lines VI—VI of Fig. 5; Fig. 7 is a detail of the lock-setting mechanism, and Fig. 8 20 is a detail of the lock.

My invention relates to improvements in car couplers of the type shown in my pending application, Serial No. 114,292, filed August 10, 1916, and consists in mechanism 25 for operating and lock-setting the lock.

Referring to the drawings, A is the coupler-head, B the lock and C the lock-set member. The lock-set member C has trunnions 2 by which it is pivoted to the coupler-head in suitable bearings 3 and may be held 30 therein by a cotter pin 4, as shown. Projecting upwardly at one side of the lock-set member C is an actuating arm 5, and extending forwardly from its central portion 35 is a lock-set ledge or shelf 6. When the lock-set member C is mounted on its trunnions 2 in the bearings 3, it is adapted to have a limited pivotal movement upon said bearings from a position in which the actuating arm 5 is upright (as is shown in 40 dotted lines in Figs. 2 and 6) to the position in which the arm 5 is inclined somewhat forwardly (as is shown in full lines in Figs. 3 and 4). When the coupler is not 45 in engagement with a corresponding coupler on an opposing car, the lock-set member C will by gravity normally assume the position shown in Fig. 4, and when two coupler-heads are interlocked, the engagement of the 50 face 7 of the opposing coupler with the actuating arm 5 compels it to assume the position shown in Fig. 6.

At the lower end of the incline on the bottom of the lock B is located a stop-shoulder 55 8, which is adapted to coöperate with the

shelf 6 on the lock-set member C, as is shown in Figs. 5 and 6. When the arm 5 of the member C is in the inclined position shown in Figs. 3 and 4, the lock-set shelf 6 is dropped down out of the way to such an extent that it forms no obstruction to the free movement of the lock down the incline 9 on the coupler-head, so that with the arm 5 in its forwardly-inclined position, the lock will slide freely to its lowermost or locked position along the incline 9 of the coupler-head. When, however, the couplers are interlocked the face 7 of the opposing coupler forces the actuating arm 5 to a substantially vertical position and rotates the lock-set member C about its trunnions so that the shelf 6 rises into the position shown in Fig. 2, in which it forms an obstruction or stop at the lower end of the incline 9 of the coupler-head. When, subsequently, as in the normal operation of unlocking, the lock B is raised, this ledge or shelf 6 will engage the shoulder or stop 8 on the lock and will thus prevent a return of the lock down the incline into the lowermost or locking position. The lock will thereafter be held supported by the movable shelf 6 until the interlocked couplers disengage or draw apart and permit the slight amount of rotation of the member C which is necessary to retract its lock-set portion 6 from the position of Figs. 5 and 6 into that of Figs. 3 and 4, after which the lock will drop into lowermost position. The lock normally remains in lowermost position both prior to and after the making of a coupler engagement, although, if desired, the parts may be placed in lock-set position.

The lock B is preferably actuated by the lifting hook 10 which underlies the lock and the end 11 of which fits into the recess 12 of the lock. The hook 10 is actuated by a chain 13, which is attached to the eye 14 in the hook and which may be passed laterally through suitable apertures in the shank of 100 the coupler.

It is obvious that various modifications may be made in the mechanism which I have shown and described herein without departing from my invention.

Having now described the nature of my invention and the best means I know of carrying the same into practical effect, I claim:—

1. In a car coupler of the vertical plane 110

type having in combination a coupler head, a gravity lock and a lock-set device, said lock-set device comprising a gravity controlled member fitted to the coupler head and adapted to assume a supporting and a non-supporting relation to the lock, said member being held in supporting position by contact with an opposing coupler head.

2. In a car coupler of the vertical plane 10 type comprising a gravity-actuated lock, a longitudinally extending recess in the coupler head, and a lock set member, said member being in form a bell crank lever pivoted to the coupler, one of the arms of the lever 15 lying in the path of the coupler head and the other of said arms being adapted to be rotated into position to bear on the bottom

of the lock and to support it in lock-set position.

3. In a car coupler of the vertical plane 20 type, a coupler head having a cavity therein, an inclined surface at the rear side of said cavity, a gravity actuated lock mounted upon said surface, a longitudinally disposed recess of L-shape in said lock and a hook 25 shaped lifter seated in said recess and engaging the lock, the said lifter being adapted to be retracted rearwardly to actuate the lock rearwardly and upwardly on said inclined surface.

JOHN WILLISON.
